SAFETY SNATCH BLOCK

Arthur Miller Hill, Tulsa, Okla., assignor to
Stanolind Pipe Line Company, Tulsa, Okla., a
corporation of Maine

Application December 30, 1938, Serial No. 248,642

1 Claim. (Cl. 254—193)

This invention relates to snatch blocks and more particularly to a new and improved type of snatch block having improved strength and superior safety qualities.

Snatch blocks are used in connection with pipe line operations and in many other connections. In the past snatch blocks have generally included a pressed steel housing and a malleable cast hook hinged on one side of the housing; a short horn cast on the body of the large hook and an oblong link hinged to the opposite side of the housing constituting the latching feature of the block. Somewhat similar devices are shown in Ferrall Patent 389,577 and Hartz Patent 527,490 which are typical of the prior art.

However, this type of snatch block has been found to be unsafe and subject to frequent failure when used for heavy duty service due to the design of the latching elements. Blocks of this sort, furthermore, unlatch very frequently when the cable is slackened off to release the load.

Both the tendency towards mechanical failure and the tendency to unlatch represent serious safety hazards which it is an object of this invention to eliminate. Other and more detailed objects, advantages and uses of my invention will become apparent as the description thereof proceeds.

In brief my invention has to do with a type of snatch block in which a draft ring or other draft member is engaged by at least one latch member hinged to each side of the body of the block and in which these members serve to latch the draft member in a strong and safe manner.

The invention will be described more fully with particular reference to the accompanying drawings in which:

Figure 1 is a front elevation of one form of safety snatch block in accordance with my invention;

Figure 2 is a side elevation corresponding to Figure 1;

Figure 3 is a sectional elevation corresponding to Figure 2 and taken along the vertical center line of Figure 1 except that the latch is shown open in Figure 3 instead of closed as in Figures 1 and 2;

Figure 4 is a partial front elevation of a modified form of safety snatch block corresponding generally to the upper portion of Figure 1; and

Figure 5 is a partial side elevation of the modified form of the safety snatch block shown in Figure 4.

Turning now to Figures 1, 2 and 3, a conventional sheave 10 is mounted between two side

plates 11 which are centrally reinforced by square plates 12 welded to the side plates. Bolt 13 passes through the side plates and square plates and is held in place by nut 14 retained by cotter pin 15.

Side plates 11 are additionally reinforced by reinforcing bars 16 of which there are four in all. These bars are welded to the side plates and terminate in enlarged ends 17 which are drilled to receive bolts 18 and 19. These bolts 18 are in turn drilled to receive cotter pins 20. The side plates, square plates and reinforcing bars are all part of the body of the block.

Bolt 18 serves as the axis for latch ring 21 while bolt 19 serves as the axis for a double latch hook 22. Thus these latching members are hinged for outward movement to permit placing a rope or cable over sheave 10.

Latch ring 21 receives draft ring 23. Double draft hook 22 latches over this draft ring as shown in Figure 2 when the latch is closed. Figure 3 shows the latch in open position. It will be noted that the construction is not only very strong but also the latch does not tend to open readily when the load is slackened off.

The bottom of my improved safety snatch block can be equipped, as shown, with member 24 which is held in place by bolts 25 passing through the lower reinforced portions of side plates 11 and equipped with nuts 26. Member 24, bolts 25 and nuts 26 hold the side plates in spaced position at the bottom and bearing tube 27, bolt 13 and nut 14 hold the side plates spaced at the center so that a rigid body structure is obtained.

This safety snatch block has proven highly satisfactory in every way under ordinary and extraordinary field conditions in pipe line work. Thus for instance, while pulling river crossing pipes this block in a 10 inch sheave size fabricated from steel parts by electrical welding was subjected to the pulling power of two truck winches pulling on it at the same time with size $\frac{1}{2}$ inch cable instead of the size $\frac{3}{4}$ inch cable for which it was designed. The block withstood this severe test which is approximately twice the stress a block would be subjected to under normal use with one truck winch.

While the snatch block of Figures 1, 2 and 3 is the preferred embodiment of my invention, I have also designed another form which is far superior to prior art snatch blocks. This second embodiment is shown in Figures 4 and 5 which are partial views, the lower portion of the block

(not shown) being identical with that of Figures 1, 2 and 3.

In the device of Figures 4 and 5 a draft hook 22' is mounted on each side of the block in the same manner as draft ring 21 and double draft hook 22 are mounted in the embodiment of Figures 1, 2 and 3 except that a headed bolt 18' is used instead of unheaded bolt 18. In other words, the form shown in Figures 4 and 5 is like that of the first embodiment except that a single inwardly-facing draft hook is used on each side instead of a draft ring on one side and a double draft hook on the other.

It will be seen that the draft hooks of Figures 4 and 5 are so shaped that there is little tendency for the device to unlatch when the load is slackened off since inner faces 28 of the draft hooks are inclined downwardly and inwardly when in latched position (Figure 5).

While I have described my invention in connection with certain preferred embodiments thereof, it is to be understood that these are by way of illustration and not by way of limitation and I do not mean to be restricted thereby but

only to the scope of the appended claim which should be construed as broadly as the prior art will permit.

I claim:

A snatch block comprising a sheave, a body portion extending on both sides of said sheave, a latch ring mounted on one side of said body portion and pivoted to move in a plane substantially normal to the plane of said sheave, a draft member carried by an elongated opening in said latch ring, a double latch hook mounted on the other side of said body portion, pivoted to move in a plane substantially normal to the plane of said sheave and constructed and arranged to engage said draft member on both sides of said latch ring, said latch ring and said latch hook being movable away from each other to give access to said sheave and movable towards each other into a position in which said double latch hook engages said draft member on both sides of said latch ring, said draft member thus being engaged symmetrically by the latch members mounted on opposite sides of said body portion.

ARTHUR MILLER HILL.
